UMBRELLA RUNNER

Filed Sept. 12, 1927

Stanley Giszczynski INVENTOR
BY Victor J. Evans

WITNESS

ATTORNEY

UNITED STATES PATENT OFFICE.

STANLEY GISZCZYNSKI, OF PHILADELPHIA, PENNSYLVANIA.

UMBRELLA RUNNER.

Application filed September 12, 1927. Serial No. 219,146.

The present invention relates to umbrellas and particularly in the construction of the head at the upper end of the umbrella stick and more especially to an improved runner, 5 and the purpose of the invention is to improve the construction and arrangement of the umbrella runner in the application of Stanley Giszczynski, filed August 30, 1926, Serial No. 132,558, now Patent No. 1,644,579, 10 dated Oct. 4, 1927.

While the present invention involves practically the same construction for holding the runner in different positions on the stick, it may be said that the essential improvement 15 embodied in the present invention consists of means for connecting the stays to the runner and the ribs to the ferrule head at the top of the stick without using a wire, which is the customary arrangement.

20 Another purpose is to provide two telescopic sleeves on the runner, or similar sleeves which may constitute the head on the umbrella stick, said sleeves having over-hanging opposed flanges engaging with each other 25 and which are slotted at opposite locations, to receive the stays which have balls or spherical members on their ends, engaging with the flanges to retain the stays in position. The fact is the balls or spherical members have 30 substantial movements between the overhanging flanges and the slots permitting a movement of the stays.

It is to be understood that the particulars herein given are in no way limitative, and that 35 while still keeping within the scope of the invention, any desired modification of details and proportions may be made in the construction of the appliance according to circumstances.

40 The invention comprises further features and combination of parts to be hereinafter set forth, shown in the drawings and claimed.

In the drawings:—

Figure 1—is a vertical sectional view 45 through an umbrella showing a runner and also the head at the top of the stick.

Figure 2—is a vertical sectional view on an enlarged scale through the umbrella runner, showing the stays connected to the runner 50 and illustrating the means for holding the runner in different positions on the stick.

Figure 3—is a cross sectional view on line 3—3 of Figure 2.

Figure 4—is an enlarged sectional view 55 through the head at the top of the umbrella stick.

Referring to the drawings, 1 identifies the stick of the umbrella, 2 the ribs, and 3 the stays, which are connected to the ribs. Sweat-ed or shrunk or otherwise secured to the upper end of the stick is a sleeve 5, one end of which has an over-hanging flange 6, and to frictionally engage telescopically with the lower end of the sleeve is a collar 7 which has an over-hanging flange 8. This collar frictionally engages with the sleeve so that the two flanges 6 and 8 are supported and their edges engaged. The flanges have opposite slots 9 and 10, and the ribs 2 are provided with balls or spherical members 11 which engage between the two flanges 6 and 8. The fact is the ribs at points adjacent the balls or spherical members engage in the slots so as to enable the ribs to have freedom of movement pivotally, and thereby insuring strength 75 and durability for the connection of the ribs to the stick.

Mounted upon the stick for movement longitudinally thereon is a runner 12 which has mounted interiorly thereof a pair of opposed collars 13, which are exteriorly tapered and mounted for operation in tapered portions 14 of the interior of the runner, there being balls 15 in cavities or openings 16 of such collars, the balls designed to engage with the stick 85 and hold the runner in different positions. Due to the balls cooperating with the tapered walls of the tapered portions 14 the balls are moved toward the stick to frictionally engage therewith and hold the runner in different 90 positions.

The exterior of the runner has a sleeve 17 with which a collar 18 telescopically engages frictionally sufficient to retain the collar in position at all times. The sleeve and the collar are provided with opposed flanges, which are curved in an over-hanging direction toward each other. These flanges 19 have opposed slots 20, which are engaged by the stays 3, allowing pivotal movement of the stays 100 due to the fact that the balls or spherical members 21 on the ends of the stays engage between the flanges. The fact is the balls permit of slight swivel movements as the stays operate, in closing and opening the umbrella.

A rod 22 is mounted for longitudinal movement in openings 23 of the opposed flanges, and connected to one end of the rod as at 23 is a collar 25 which connects with a sleeve 110 26 connected to one of the collars 13, there being a spring 26 interposed between one of

the collars 13 and a collar 27 threaded into one end of the runner so as to retain one of the collars 13 in a position so that its ball may co-act with the stick to hold the runner in position.

The other collar 13 is carried by a similar sleeve 28 which is guided through the other end of the runner and is also guided upon the rod 22 through the medium of a ring 29, there being a spring 31 interposed between a sleeve 30 and the last mentioned collar, so as to hold such last mentioned collar in a position whereby its ball may engage with the stick to further hold the runner in position. The rod has a head 32 which is engaged by the thumb while the ring has extensions 33, which are engaged by the fingers, for releasing the collars 13.

It will be noted that the manner of connecting the stays to the runner by the spherical balls and the slots eliminates the use of the usual wires as commonly employed in the construction of umbrellas.

The invention having been set forth, what is claimed is:

In an umbrella, the combination with a stick having a plurality of stays, of a runner

slightly adjustable on the stick and comprising two sections with their adjacent ends telescopedically and frictionally united, said adjacent ends having opposed flanges overhanging and curved toward each other and provided with registering opposed slots to receive certain ends of the stays, said ends of the stays having spherical members, the inner portions of the overhanging curved flanges being of such curvature as to movably receive the spherical members of the stays, the opposite end portions of the runner provided with compressing devices associated with frictional means to hold the runner in different positions, and means passing through the overhanging flanges and operatively associated with the compressing devices and being manually actuated in association with both of said devices for releasing the last named frictional means to permit adjustments of the runner, said compression devices cooperating with the two sections of the runner to prevent their disconnection.

In testimony whereof he affixes his signature.

STANLEY GISZCZYNISKI.
